HAT OR THE LIKE

Helena Z. Chamberlin, San Diego, Calif.

Application September 27, 1948, Serial No. 148,791

Term of patent 3½ years

(Cl. D3—13)

To all whom it may concern:

Be it known that I, Helena Z. Chamberlin, a citizen of the United States, residing at San Diego, in the county of San Diego and State of California, have invented a new, original, and ornamental Design for a Hat or the like, of which the following is a specification, reference being had to the accompanying drawing, forming a part thereof.

In the drawings:

Fig. 1 is a front view of a hat, showing my new design as it appears in collapsed position;

Fig. 2 is a rear view thereof;

Fig. 3 is a front perspective view of the hat as it appears when worn;

Fig. 4 is a rear perspective view thereof.

I claim:

The ornamental design for a hat or the like, substantially as shown.

HELENA Z. CHAMBERLIN.
